UNITED STATES PATENT OFFICE.

FREDERICK M. GAUME AND JAMES M. GAUME, OF DANVILLE, KANSAS.

AUTOMATIC WEIGHING-MACHINE.

SPECIFICATION forming part of Letters Patent No. 760,861, dated May 24, 1904.

Application filed February 12, 1904. Serial No. 193,247. (No model.)

To all whom it may concern:

Be it known that we, FREDERICK M. GAUME and JAMES M. GAUME, citizens of the United States, residing at Danville, in the county of 5 Harper and State of Kansas, have invented certain new and useful Improvements in Automatic Weighing-Machines, of which the following is a specification.

Our invention relates to improvements in 10 automatic weighing-machines, the objects of which are, first, to provide an automatic weighing-machine which shall automatically receive, weigh, and discharge in amounts of predetermined weight substances generally 15 of a granular nature—such as sand, coal, &c., and grains, millstuffs, and the like—with speed and accuracy; second, to so construct an automatic weighing-machine that it shall be operated solely by the gravity of substance 20 being weighed and that all delicate and unreliable mechanism or parts shall be eliminated, thus providing an automatic weighing-machine which shall be cheap in cost of manufacture, reliable in its operation, very durable, and not at all liable to get out of order. 25 We attain these objects by the mechanism illustrated in the accompanying drawings, in which—

Figure 1 is a vertical section cut on the 30 line $\alpha\alpha$ seen in Fig. 2 and also of cover and hopper. Fig. 2 is a top plan with cover and hopper removed. Fig. 3 is a side elevation. Fig. 4 is a side elevation of certain equivalent but differently-formed parts.

In the preferred form of our invention 35 (seen in Figs. 1 2 3) a shaft 1 rotates in bearings 2 on frame 3 and carries two annular disks or end pieces 4, connected by fixed partitions 5, 6, and 7, subdividing the space between disks 4 into three rotatable compartments or bins 8, 9, and 10. Each of said bins is provided with a rotatably-attached outer end 8^a, 9^a, and 10^a, respectively, of suitable length to rotate on rods 8^b, 9^b, and 10^b, respectively, 40 to form sloping end gates, each for its respective bin, as seen at 8^a, 9^a, and 10^a in Fig. 1, and the free edge of each end gate by the successive rotations of its bin will be brought into and gravitate to the position seen at 9^a 45 in Fig. 1. Should centrifugal force cause

free edges of end gates 8^a, 9^a, and 10^a to rotate outward, said edges will be stopped by their respective abutments 11, 12, and 13. (Seen in Figs. 1 and 2.) Shaft 1 carries upon its extremities the two triangular-shaped 55 cams 14 and 15, having apexes 14^a, 14^b, and 14^c. In Fig. 1 is seen one of two members 17, provided with a preferably hardened and polished surface plate 16, resting upon apexes 14^a and 14^b. Said two members 17 unite and 60 are formed with a graduated scale-beam 17^a, carrying weight 18, adjustably secured along said beam at any desired point by set-screw 19. Cover 20 is provided with hopper 21, into which in the operation of my invention gravitates the substance 22 which is being weighed, 65 as seen in Fig. 1. When the proper weight of substance 22, as indicated by weight 18 on beam 17^a, has gravitated from hopper 21 into bin 8, the gravity of substance 22 will cause 70 bins 8, 9, and 10 to rotate, driving shaft 1, carrying triangular cams 14 and 15 and their apexes 14^a, 14^b, and 14^c and by said rotation of apexes beneath members 17 cause members 17, scale-beam 17^a, and weight 18 to be lifted 75 to the position seen in Fig. 3, and the further rotation of bins and attached parts will allow weight 18 and its attached parts to gravitate to the position seen in Fig. 1. It will be seen by referring to Fig. 1 that by the before-80 described rotation of bins 8, 9, and 10 partition 7 and vertically-suspended end gate 9^a will rotate past and beneath hopper 21 until they have by gravity been caused to occupy the respective positions of bin 8 and end gate 85 8^a; and it will be further seen and understood that the narrow edge of partition 7, passing beneath hopper 21, will quickly and accurately bring bin 9 in position to receive substance 22 from hopper 21 and that the vertically-suspended end gate 9^a will neither deflect nor retard substance 22 from entering 90 bin 9. The before-described rotation of bins 8, 9, and 10 will continue so long as substance 22 is supplied to hopper 21, and after being 95 weighed substance 22 will gravitate from bins 8, 9, and 10 (in succession) through discharge-spout 23, as seen in Fig. 3. A cord or rod 17^c is attached to member 17 for the operation of any ordinary tally-box. (Not shown.) 100

While we have shown and described our invention as having a hopper 21, cover 20, and a discharge-spout 23, it is evident that such parts could be omitted where circumstances 5 do not require them without impairing the operation of our invention, and we reserve the right so to do.

Where frictional wear upon face-plate 16 and apexes 14^a 14^b 14^c is excessive, owing to 10 excessive weight of quantities of substance 22, shaft 25, bearing-plates 26, friction-rolls 26^a, 26^b, and 26^c, actuating one or more members 27 of a scale-beam 27^a, pivotal at 27^b and provided with a weight 28 and set-screw 29, 15 as seen in Fig. 4, are used as equivalents to shaft 1, cam 14, apexes 14^a 14^b 14^c, members 17, scale-beam 17^a, pivotal attachment 17^b, weight 18, and set-screw 19, as seen in Figs. 1 and 3, in the order given, and we further reserve the right to use any antifrictional bearings or to so modify the relative arrangement of parts as to comply with the various situations in which our invention may be used 20 without departing from the spirit of our invention.

We are aware that automatic weighing-machines are in use in which a series of rotating bins actuate a weighted lever or scale-beam by gravity of substance being weighed 25 therein, and therefore do not broadly claim such as being our invention; but all such inventions of which we are aware are either controlled by fragile or complicated parts liable to get out of order or have the outer 30 ends of their rotating bins open, leaving substance weighed thereby to press outwardly against the inner surface of a box or casing inclosing them (not shown) and in which the various adhesive tendencies of said substances 35 to the inner surface of said box and the lodgment and binding of small particles of substance between said box and the edges of the annular ends of said open bins act as irregular resistances to the rotation of said bins, thereby causing irregular and inaccurate weighing; 40 but we are not aware that automatic weighing-machines have ever been known or used prior to our invention hereof in which substance being weighed rests solely against the 45 inner surface of one of a series of rotating bins unretarded by frictional contact of substance weighed with any fixed part—such as the cover, casing, or discharge-spout—except where burdened with fragile or complicated 50 parts liable to get out of order, as hereinbefore stated.

Therefore what we claim as new, and desire to secure by Letters Patent, is—

1. In an automatic weighing-machine, the

combination with a series of rotatable bins, 60 having fixed partitions extending between said bins to the limits thereof, of one end gate in each bin, each end gate being so pivotally attached to the sides of its bin as to operate by gravity in the manner and for the purposes 65 specified.

2. In an automatic weighing-machine, three bins, in one annular series, mounted upon a rotatable shaft, having fixed bearings and supports, and carrying rigidly secured upon the 70 extremities of said shaft, one or more triangular cams, each cam having three outward projections or apexes, acting in conjunction with a surface-plated member of a weighted lever or scale-beam for operatively holding 75 and releasing said bins, as specified.

3. In an automatic weighing-machine, a series of three rotatable bins, having fixed partitions extending between said bins, to the 80 limits thereof; each bin having one end gate pivotally attached at its upper edge to the sides of its bin and oscillatable therein; the whole being secured upon a rotatable shaft, having fixed bearings and supports, and provided with one or more triangular cams, each 85 cam having three apexes; in combination with a weighted lever or scale-beam having a surface-plated member normally resting upon two of said apexes, and means for rotating said bins, shaft and cam as specified.

4. In an automatic weighing-machine the combination with a series of three rotatable bins, having fixed partitions extending between said bins, to the limits thereof, and a pivotally-attached end gate in each of said 95 bins, a triangular cam and a weighted lever for operatively holding and releasing said bins; of a cover and a hopper above, and of a discharge-spout beneath said bins, as shown and specified.

5. In an automatic weighing-machine, a series of three rotatable bins, having fixed partitions extending between said bins, to the 100 limits thereof and a pivotally-attached end gate in each of said bins, the whole, operatively rotated by gravity of substance being weighed, and having a triangular cam, and an adjustably-weighted lever or scale-beam, one or more members of which is provided with means for operating any ordinary tally-box.

In testimony whereof we affix our signatures in presence of two witnesses.

FREDERICK M. GAUME.
JAMES M. GAUME.
